having a pin portion 50 extending partly into the bore 45 to act as a stop for the shoulders formed on the shaft 46 by the reduced portion 48 thereof and thereby limit the movement of the shaft 46 in either direction, longitudinally of the projector. The forward end of the shaft 46 extends through the bore in the ear 44 and this portion of the shaft 46 is provided with a longitudinal bore 51 and a transverse bore 52. In the bore 51 there is disposed a stub shaft 53 held therein by screw 54 (Fig. 7), and having on its inner end a tooth 55. This tooth is adapted to engage with a spiral groove 56 in a transverse shaft 57 extending through bore 52 and journaled at 58 and 59 in the ear 44. The outer end of this shaft 57 is provided with a thumb element 60 and an indicator dial or disk 61 on which suitable indications such as 62 may be disposed as desired. A spring 63 is disposed beneath the dial 61 and the bottom of a recess 64 in the ear 44 in which it is disposed. Another bore 65 (Fig. 2) in the ear 44 holds a spring 66 which presses a ball 67 into one or another of several notches or indentations 68 on the under side of the dial 61.

Disposed and housed within the rear face of the turret element 15 are three auxiliary tubes such as 69, 70 and 71, Figs. 4 and 5, the axes of which are in alignment with the axes of the lens tubes 25, 26 and 27 in the front of the turret element 15. These tubes 69, 70 and 71 are mounted on and carried by a spider frame such as 72, (see Fig. 6) mounted on a central rod 73 slidably journaled in a sleeve 74 mounted centrally of the turret element 15 and extending from the rear face thereof. Between the rear face of the turret element 15 and the rear face of the spider member 72 there is disposed a spring 75 around the rod 73 and the sleeve 74. The rod 73 and with it the spider 72 carrying the tubes 69, 70 and 71 may be slid in and out of the turret element 15 and the spring 75 will always tend to keep the tubes in the position outwardly shown in Fig. 6. This position is the one in which these tubes on their outer faces will bear against the adjacent face of a film aperture gate, not shown. Between each pair of the tubes 69, 70 and 71 there is disposed on the spider element 72 a shallow depression 76 in which is disposed a triangular plate such as 77, (see Fig. 3) held therein by a screw 78. This plate in each instance has at its bottom a cut 79 therein. Back of the plate 77 adjacent the cut 79 there is rotatably mounted by screw 80 a plate 81 which carries certain indicia such as 82. It will be noted that the indicia 82 are disposed at the rear of the turret in association with the auxiliary tubes, each indicia being disposed adjacent the lenses to which its color and character are limited so that as the lens is aligned with the optical axis, 60 near the center of the machine, its corresponding indicia is disposed opposite it near the top of the machine so that it is readily observable by the operator either through the glass of the door or when the door is open.

65 Operation of the device

Having now described the parts and their assembly and part of their cooperation, the actual functioning will be described.

70 To rotate the turret.—The turret member 15 is merely gripped in the hand, turned against the retarding action of the plurality of balls 19 lying in the notches 18 in the ring 12. These notches are so disposed that when the balls lie therein at least one of the lens tubes is in proper

alignment with the desired optical axis. When a new lens is to be aligned, the turret is turned until the desired lens is in position and when it is so the balls will click into position, and the operator can tell by the slight resistance thus offered that the proper position has been reached.

The lenses properly located in their holding sleeves are introduced into the holding tubes and are fastened therein by tightening of the screws 28.

To focus the lenses.—Referring particularly to Fig. 4, the turning of the thumb piece 39 will turn the shaft 37. This being threaded in the fixed plug 35 will cause the shaft 37 to move to the right or the left in accordance with the turning movement thereof and will advance or withdraw the lens tube which is connected to that particular shaft 37 since the lens tube ear such as 29 is screwed to the sleeve 30. This sleeve 30 is forced to the right by means of pin or key 43 and to the left by means of plug 38. As the lens tubes are thus focused their stop limits are also determined by the pin 50 engaging with the shoulders on the stub shaft 46 at the bottom of the turret 15. This is true because as the ear 44 on each lens tube moves to the right or the left it carries with it the transverse shaft 57 and the stub shaft 46 which slides in the bore 45 of the turret element 15. It will be understood that each lens tube can be thus separately focused. The construction above described with regard to one lens and its holder and operation applies to each and all of them both as to the focusing and as to the lateral shifting of the tubes for the alignment of the same tube with one or more of several different projection axes.

To shift the lenses laterally.—Referring to Figs. 4 and 7 particularly, the rotation of the thumb piece 60 will rotate the shaft 57 and by the engagement of the tooth 55 in the spiral groove 56 will laterally shift the ear 44 and thus will likewise shift the lens tube in question in the desired direction and this partial rotation will take place around the axis of the bore 32 of turret member 15 since the lens tube carrying the ear 44 is mounted on the sleeve 30 which is slidably and rotatably mounted in said bore. The dotted center lines shown in Fig. 8 indicate the amount of swing given to the lens mounts upon the axis of sleeve 30 to align the lenses with the various optical axes as above mentioned, which correspond to the optical axis of the regular film, the "Movietone" regular film and "Movietone Grandeur" film.

The operation of focusing the lenses will not affect the operation of the shift device since the stub shaft 46 as described can move longitudinally to the limits of the stop pin 50 in either direction. The indicia 62 will tell which axis the tube is in alignment with.

To operate the film aperture gate.—When the film has to be threaded or taken out of the machine for one reason or the other, it is necessary to pull back the gate from the aperture plate and when this takes place the light tubes such as 69, 70 and 71 must be moved back with the gate against which they normally are in contact. This is effected by reason of the fact that the tubes above mentioned on the spider 72 can be moved back against the action or resistance of the spring 75. The position of the lenses in the turret with respect to the main projection axis will be indicated by the indicia such as 82, see Fig. 3. In the drawings the indicium labelled N will indicate that the lens with which it is associated is to be used in alignment when "Movietone" film is being used in the machine. The indicium G when a wide or "Grandeur" film is employed. The indicia R

BREAKER FOR ELONGATED MATERIAL

Bethune G. Klugh, Birmingham, Ala., assignor
to Swann Fertilizer Company, a corporation of
Delaware

Application September 2, 1931, Serial No. 560,783

10 Claims. (Cl. 83—6)

My invention relates to apparatus for breaking elongated fragile bodies into particles of uniform size and has for its principal object the provision of apparatus of the character designated which shall be simple of design, economical of manufacture and which shall operate with the production of a minimum of fines or irregular sized particles.

A further object of my invention is to provide breaking apparatus which shall be particularly adapted for breaking elongated fragile bodies and which shall be effective to break such bodies into uniform length particles, with a minimum of waste and which shall have a relatively large capacity.

In my copending application, Serial No. 558,669, filed August 22, 1931, and relating to a process for producing concentrated fertilizer, there is described and claimed a process in which concentrated plant nutrient salts such as monoammonium phosphate, diammonium phosphate and potash salts are first formed into a dough-like paste and extruded in the form of relatively long cylindrical bodies. These bodies are dried and broken into particles of uniform length suitable for handling in ordinary farm drilling machinery.

The apparatus disclosed and claimed in this present application is particularly adapted for breaking the dried cylindrical bodies of concentrated fertilizer as described in my before mentioned application and will be described with relation thereto, though it will be apparent to those skilled in the art that it may be employed for uniform breaking of many fragile materials other than concentrated fertilizer salt mixtures.

In the breaking of extruded bodies of salt mixtures into uniform particles there are certain difficulties to be overcome which resist breaking apparatus as heretofore known to me. The elongated extruded bodies are of substantially uniform diameter but of varying lengths. They are of a substantially uniform compression resistant strength throughout the individual sections and have no distinctive planes of relative weakness. Hence any crushing action, such as rolls or hammer mills tend to break the bodies into heterogeneous shapes and sizes responsive to the haphazard directional compressive and impact action that is thereby exerted on them.

With apparatus made in accordance with my invention the bodies are broken in planes at right angles to the longitudinal axis thereof and in uniform lengths. This is accomplished by a pair of cutter rolls provided respectively with longitudinal and transverse grooves on the respective

faces thereof. By proper positioning and adjustment of these rolls and by control of the direction of rotation and relative angular speeds thereof (to be more particularly described later), I am enabled to control the direction and magnitude of rupturing force and the depth of cut on each body so that it is cut into uniform length sections or particles. I am furthermore enabled to so control the feed to the said rolls whereby the passing of superimposed extruded bodies between the rolls is prevented.

Apparatus embodying features of my invention is illustrated in the accompanying drawing forming a part of this application, in which:—

Fig. 1 is a sectional elevation of apparatus embodying features of my invention; 15

Fig. 2 is an end view, drawn to a larger scale than Fig. 1, of the cutter rolls in operation; and

Fig. 3 is a sectional view taken along the line III—III of Fig. 2. 20

Referring to the drawing for a better understanding of my invention, I show a lower cutter roll 10 and an upper cutter roll 11. The lower cutter roll 10 has a shaft 12 mounted in bearings 13 and the upper cutter roll 11 has a shaft 14 mounted in bearings 16. The bearings 16 are made adjustable by means of adjusting screws 17 whereby the rotational axes of the two rolls may be maintained in true parallelism. The lower roll 10 may be driven through a pulley 18 from any suitable source of power. The upper roll 11 is driven from the shaft 12 through a reduction gear train embodying gears 21, 22 and 23, so that the upper roll 11 rotates at a greater speed than the lower roll 10. Preferably the upper roll has a speed ten times that of the lower roll. 25

The lower roll 10 is provided on its periphery with longitudinal grooves 27 separated by relatively sharp ridges 28. The upper roll 11 is provided with similar grooves 31 extending transversely around the periphery of the roll and separated by relatively sharp ridges 32. 30

The grooves in the upper roll 11 are kept clean of fine material by means of a rotary brush 33 driven from the shaft 14 through gears 24 and 26. Mounted to the rear of the lower roll 10 on a suitable frame 34 is a motor 36 which drives a rotary brush 37 for cleaning the lower roll 10. 35

The motor 36 is mounted upon the frame 34 so as to reciprocate thereon. This is brought about by attaching the motor frame to a plate 38 having a depending stirrup member 39. The stirrup member 39 is provided with a slot 41 adapted to cooperate with a pin 42 carried by a belt 43. 50

The belt 43 rides on pulleys 44 and 46, the latter being driven from the shaft 12 by means of bevelled gears 47, shaft 48 and gears 49. By the means just described the motor 36 with its brush 37 is caused to reciprocate along the lower cutter roll 10 and keep the grooves 27 clean.

The grooves 27 have a depth and contour which are related definitely to the size of the material to be broken. For example, with material such as extruded salts, having a diameter of 5/64 of an inch, the grooves are made 3/64 inch in depth, with a cross sectional radius of 7/128 inch. This provides a trough in which the elongated extruded bodies of 5/64 inch diameter may freely rest.

The grooves 31 in the upper breaker roll are preferably made of the same cross sectional dimensions and shape and with the same intervening cutting edges as those of the lower cutter roll 10 but, as seen from the drawing, are at right angles to the grooves 27.

The two rolls are adjusted to accurate parallelism with a distance of approximately 1/64 inch between the cooperating surfaces when breaking material of 5/64 inch diameter. This spacing of the rolls of course would vary somewhat with the size material being treated and the spacing given is understood to be only for that particular size and kind of material. With such spacing and with material of 5/64 inch diameter, it will be evident that a given piece of material such as 51 lying in one of the grooves 27 will project above the grooves 2/64 of an inch and be subject to a cut from the cutting edge of the cooperating roll of 1/64 of an inch. This relative depth of cut into the section to be broken is very important in the production of uniform lengths and avoidance of breaking the sections into irregular shapes. In this example, which corresponds to actual practice, the cut into the section by the cutting edge 40 is $\frac{1}{5}$ the diameter. The sections being relatively brittle, are ruptured in a plane at right angles to their axes, with about this relative cutting depth. If the depth of cut into the section is relatively greater, (for instance $\frac{1}{2}$ the section), the tapered bases of the cutting edges will exert an added longitudinal pressure component upon the sections, from the upper half of the ends of the portion so cut, as to cause a longitudinal splitting of the said sections thus producing irregular shapes and defeating the object of the invention.

The contour of the groove is likewise important in producing regular uniform lengths with preservation of cylindrical sections. The radius of this groove, slightly greater than that of the section to be cut, provides a trough giving the said section a full surface bearing so that the cutting force from the opposite side is effectively resisted, and directed at right angles to the axis. Furthermore, the trough being wider than the sections, permits the sections a slight rolling movement toward adjacent ridges upon contact with the cooperating cutting ridge.

The uniform spacing of the grooves and cutting edges insures that the material will be cut in uniform lengths corresponding to the spacing of the cutting edges of the roll opposite the groove in which the material is lying. This is illustrated in Fig. 3 where a piece of material 52 lying in a groove 27 is shown as being cut by the cutting edges 32.

The upper roll 11 is preferably mounted to the rear of a vertical plane passing through the axis of roll 10. I have found that the best results are obtained by so mounting the two rolls that a plane 75 joining the axes of the two rolls makes an angle

of approximately 45 degrees with a vertical plane passing through the axis of the lower roll 10. With this arrangement, the material may be fed onto the upper surface of the roll 10 as by means of a chute 53.

In operation the two rolls are rotated in the same direction, the lower roll running at around 10 R. P. M. and the upper roll at a speed of substantially ten times that of the lower roll or around 120 R. P. M. The direction of rotation of the lower roll 10 therefore is such as to carry the material to be broken between the rolls. Inasmuch as the upper roll 11 rotates in the same direction as the lower roll 10, its lower side cooperating with the upper surface of the roll 10 will be moving in a direction opposite to that of the roll 10.

It is obvious that the elongated uniform diameter cylindrical sections will be cut into uniform lengths with preservation of the cylindrical form, and with faces at right angles to their longitudinal axes, only when they pass through the cutting zone, with full surface contact in the groove on one side and with action of the cutting edges their full length on the other side. If any of the sections pass between the rolls superimposed one upon the other, or in any position other than individually in full length contact with the coating elements of the respective rolls, they will be subjected to complex crushing forces, that will 30 break them into heterogeneous shapes and sizes.

Therefore the guiding of the sections into the cutting zone in such positional contact is an essential factor in consummating the object of this invention. With the contour and relative angular arrangement of the grooves and cutter edges, and the spacing of the effective elements of the two respective rolls aforescribed, this guidance of the sections is effected by the relative peripheral speeds of the two rolls.

The mass of sections fed by gravity from the chute 53, on the top surface of the lower roll, will naturally be arranged in varying positions and will be so conveyed by the rotation of the lower roll toward the angular gap approaching the cutting zone. The surface of the upper roll travelling in opposing direction and at much greater velocity than that of the lower roll, sets up a repelling force in excess of the conveying force of the surface of the lower roll. Hence all bodies being loosely conveyed on the surface of the lower roll, move into the repelling influence of the upper roll and will be thereby ejected backward from a point tangent to the pitch line of the upper roll from the point of such contact. However, those sections lying wholly in the grooves of the lower roll, as well as those lying in full contact across the cutting edges of the lower roll and in line with a groove in the upper roll, do not reach this contact with the repelling influence of the upper roll until they are sufficiently within the closing gap to be carried through the cutting zone.

The sections not in proper guidance and so thrown backward remain in the circuit of conveyance and ejection until they are brought into proper position in relation to the grooves, to be carried into the cutting zone. The natural tendency of the movement of the cylindrical sections, on the grooved surface described, is to roll into a groove and there remain at rest under conveyance of the lower roll. Hence with the area of conveying surface of the upper roll between the chute and the closure with the upper roll, there will normally be ample contacts of the sections 75
